ABRAHAM SATZMAN, OF NEW YORK, N. Y.

AUXILIARY LOCK FOR DOORS.

1,054,450.

Specification of Letters Patent. Patented Feb. 25, 1913.

Application filed June 29, 1912. Serial No. 706,572.

To all whom it may concern:

Be it known that I, ABRAHAM SATZMAN, a citizen of the United States, and a resident of the city of New York, borough of Manhattan, in the county and State of New York, have invented a new and Improved Auxiliary Lock for Doors, of which the following is a full, clear, and exact description.

- 10 Among the principal objects which the present invention has in view are: to provide means whereby a door may be secretly locked in closed position and from a distance, to prevent the unauthorized exit of 15 a person from a room without the knowledge of the one in authority; to provide means for operating a lock of the character named, and for releasing the same in the presence of a person and without his knowledge; to provide an audible alarm operable by the lock when closed, and means for operatively controlling said alarm; and to provide a simple, efficient and durable mechanism for operating said lock.
- 20 Reference is to be had to the accompanying drawings forming a part of this specification, in which similar characters of reference indicate corresponding parts in all the views, and in which—
- 25 Figure 1 is a diagrammatic view showing in plan a fragment of a store, the entrance door whereof may be secured with an auxiliary lock constructed and arranged in accordance with the present invention, and 30 showing the disposition of the alarm external to the store; Fig. 2 is a diagrammatic view showing in elevation a fragment of the front wall of a store and of the closure door therefor, and an auxiliary lock for 35 said door and means for secretly operating the same; Fig. 3 is a detail view, on an enlarged scale, showing the bolt and means for automatically placing the same in operative position to lock the door; Fig. 4 is a 40 detail view, on an enlarged scale, in perspective, showing means for setting and releasing the auxiliary lock; and Fig. 5 is a detail view, on an enlarged scale, showing 45 in perspective a small fragment of the closure door and striker plate for the bolt of the auxiliary lock, and means for preventing the operation of said lock.

The present invention is particularly designed to provide for the protection of a 50 salesman in a store where the goods are ex-

posed within the reach of a customer in a manner to enable him to make away with the same.

With this object in view, the invention primarily consists in furnishing a concealed locking device to engage the door while in closed position, to prevent the opening thereof by the operation of the customary lock with which the door is provided; and to provide means conveniently accessible to the 60 salesman, to be operated by him while interviewing a customer, and without the knowledge of the customer.

It further consists in providing means for releasing the lock also without the knowledge of the customer and prior to the departure of the customer.

As an adjunct to my invention, there is provided an electric bell signal, the operating circuit of which is closed automatically 75 by the auxiliary locking device and when the lock is operated, the operating circuit of said bell being manually controlled, to at will discontinue the same.

In the accompanying drawings the auxiliary lock consists primarily of a bolt 10. The bolt 10 is guidably mounted in sliding bearings 11. The bearings 11 are rigidly mounted on a plate 12. The plate 12 is fixedly secured to the standing structure by 80 means of screws 13. To provide a seat for the plate 12, the frame for the door A is partially cut away to form a pocket for the said plate 12, which pocket is covered or concealed by the facing of the frame of 85 said door.

The door A, as shown in Fig. 5, is usually provided with a striker plate 14, and the striker plate 14 is perforated to 90 form a bolt-hole 15. In mounting the plate 14 and the plate 12, care is exercised that the bolt 10 registers with the hole 15 when the door A is in closed position. The bolt 10 is shot or moved forward into the hole 15 by spiral springs 16, which, as seen in 95 Fig. 3, are anchored to posts 17 and a cross bar 18, the latter being rigidly attached to the bolt 10.

Normally, the bolt 10 is held retracted, being drawn back from the striker plate 14 and the bolt-hole 15 thereof by a flexible connector 19. The connector 19 is preferably constructed in sections, said sections being united by bell cranks 20, whereby the connector 19 may be extended to a station 100

105

110

distant from the door A, and may be led thereto secretly and through a tortuous route if such be necessary or desired. The end of the connector 19 adjacent the bolt 10 is connected to the cross bar 21 of a bail 22. The bail 22 is pivotally connected to the bar 18. The opposite end of the connector 19 is united to a swinging member 23, which is extended from the under side of a 10 foot treadle 24. As seen in the drawings, the normal position of the foot treadle is flush with the floor line B of the standing structure or store. I usually prefer that the treadle 24 should be a board corresponding 15 to the floor boards of the store, and should be pivotally mounted thereto by a hinge 25. It will be understood that this structure may be varied without passing beyond the scope of the present invention, the intention being to supply a foot-operated means 20 for drawing upon the connector 19 to retract the bolt 10 from its engagement with the door A and the striker-plate 14 thereof. I have adopted the construction shown and 25 above described because it has seemed to afford more secrecy in the equipment. It will be understood also that while I have shown in the accompanying drawings but one treadle 24 and one operating station, 30 there may be adopted a series of such stations and a number of treadles 24, as indicated in Fig. 1 of the drawings.

To hold the treadles 24 in the normal position, wherein the bolt 10 is retracted, I 35 have provided a pivot latch 26. The latch 26 is preferably united to a standard 27 by means of a hinge 28, as seen best in Fig. 4 of the drawings. The latch 26 is normally controlled by a weight 29 to move out of the 40 path of the treadle 24, and is only disposed so that the bent portion 30 extends over the treadle when the operating cable 31 is drawn upon by the attendant, which is done when the attendant, by placing his foot on 45 the treadle 24, depresses the same from the released position shown in dotted lines in Fig. 2 to the captured position shown in full lines in Fig. 2.

The door-closing mechanism above described is provided with an electric alarm bell C, which is normally positioned outside the store, the purpose of which is to alarm the neighborhood in the event of an attack made upon the attendant or salesman within 50 the store. It is the design that the alarm C can be operated only when the door A is closed, and the bolt 10 is shot in holding position to said door. When the bolt is shot, as seen in Fig. 3 of the drawings, the bar 32 55 impinges upon a plate 33 mounted on the plate 12. The plate 33 is suitably insulated from the plate 12, and forms a terminal for the electric circuit incorporating the bell C, the battery D and the switch E. The wires 60 34, 35 and 36 constitute the remaining ele-

ments of the electric circuit. The wire 34 is electrically connected with the plate 33, while the wire 35 is electrically connected with the plate 12. When the switch E is closed, it will be seen that the shooting of 70 the bolt 10 to enter the bolt-hole 15 and the door A causes the bar 32 to impinge upon the plate 33 and close the electrical circuit through the bell C and the battery D, thereby causing the former to sound an 75 alarm. It will also be understood that when the switch E is kept open, the closing of the door 32 upon the plate 33 does not have the effect above mentioned.

The slide plate 37 is provided to cover 80 the hole 15. To do this, the plate is raised, using for this purpose the nail nick 38. The plate 37 is used as a safety device to prevent the accidental shooting of the bolt 10 while the owner or salesman is out of the 85 store equipped with the auxiliary locking device. By mounting said plate in the slides 39, to operate by gravity therein to uncover the hole 15, provision is made against the accidental movement of said plate to cover 90 the hole 15, placing thereby the auxiliary locking apparatus out of commission in a moment of emergency.

The auxiliary lock for doors above described is operated as follows:—When a customer 95 enters the store equipped with this auxiliary lock, under suspicious circumstances or at a time when the salesman or attendant is open to assault or in condition to be robbed by the customer snatching any article exhibited, 100 and making away with the same, the salesman, in exhibiting his goods, moves to a position where he may place his foot on one or other of the treadles 24. The door A is naturally closed after the customer gains 105 admittance to the store. The salesman, by now pressing upon the treadle 24, permits the weight 29 to overbalance the latch 26, causing the same to rotate on the hinge 28, to remove the bent portion 30 from engagement with the treadle 24. The salesman now 110 permits the treadle 24 to be quietly raised, being influenced thereto by the effect of the springs 16 upon the connector 19 and parts connected therewith. The springs 16, in 115 thus pulling upon the cross bar 18, move the bolt 10 to seat within the hole 15. Without the customer being aware, the door is now locked against egress until permitted by the salesman operating the treadle 24. If, in the 120 course of the business, it proves that the salesman's suspicions are unfounded, he, by quietly pressing upon the treadle 24, swings backward the bar 23, pulling thereby upon the connector 19 and parts connected therewith, to retract the bolt 10 from engagement 125 with the hole 15. When the treadle 24 is in full depressed position, as seen in Fig. 2 of the drawings, the salesman, by pulling upon the cable 31, lifts the latch 26 and the 130

135

weight 29 connected therewith, until the bent portion 30 thereof passes above and thereafter holds the treadle 24. By the arrangement and operation of the auxiliary lock in the manner above described, the salesman has protected himself against the machinations of a sneak-thief or more dangerous assault with intent to rob, on the part of a burglar, and if the suspicions have proved false, the customer is permitted to depart without having become aware of the fact that he was held in suspicion. Normally, the switch E is drawn to open-circuit position. When, however, the thief having started to get away with his booty, the salesman has at hand the switch, which may be closed by a quick movement on his part, and the alarm operating the bell C thereafter continues until the switch E is thrown to open-circuit position, or the bolt 10 is withdrawn from locking engagement with the door.

While I have herein shown and described the auxiliary lock as applied to one door, and as operated from one station, it will be understood that a number of locks may be employed, all of which are operable by each of the treadles 24. The result of the operation is that a thief finds that he is trapped within the store, to be there captured when the alarm has aroused and called assistance. It will also be understood that a bolt thus employed might be screw-threaded to secure the same within the hole 15, or smooth to rest therein. During the absence from the store on the part of the owner, the plug thus employed would be inserted in the hole 15. On

the return of the owner, the plug would be withdrawn and the auxiliary lock thereafter would be in operative condition.

Having thus described my invention, I claim as new and desire to secure by Letters Patent:—

1. An auxiliary lock such as described, comprising a spring-actuated bolt mounted within and concealed by the frame of a door, said bolt being adapted for extension from said frame, to engage said door; automatic means to normally move said bolt to engage said door; a pivoted treadle mounted at a station distant from said door; transmission means connecting said treadle and said bolt, to retract said bolt; and a latch to hold said treadle in bolt-retracting position.

2. An auxiliary lock such as described, comprising a spring-actuated bolt mounted within and concealed by the frame of a door, said bolt being adapted for extension from said frame, to engage said door; automatic means to normally move said bolt to engage said door; a pivoted treadle mounted at a station distant from said door; transmission means connecting said treadle and said bolt, to retract said bolt; a latch to hold said treadle in bolt-retracting position; and means to automatically throw said latch when said treadle is released.

In testimony whereof I have signed my name to this specification in the presence of two subscribing witnesses.

ABRAHAM SATZMAN.
